PRINTING APPARATUS

John K. Bruce, South Pasadena, Calif., assignor to Albert Van Luit & Co., Los Angeles, Calif., a corporation of California

Filed Mar. 11, 1957, Ser. No. 645,207

2 Claims. (Cl. 101—425)

The invention relates to apparatus for printing a continuous pattern on a material by means of an intermediate roller.

The use of metallic pigments in printing patterns on decorative material such as wall paper, fabrics, etc. has intensified the problem of residual pigment being carried into printing contact with the material by successive turns of the printing roller. For instance, in rotogravure printing such as used to give wall paper or similar materials a decorative background upon which to print a foreground pattern, an intermediate roller with a gelatinous printing surface is commonly used. A material such as silicone may be added to the basic gelatin to make the surface impervious to pigment penetration. A pattern roller having an embossed surface is conventionally continuously pigmented as it rotates. The pattern roller rotates in contact with the printing roller so that the continuous pattern is impressed in pigment on the printing roller. The actual transfer of the pattern to the material is made by the printing roller as the material is passed between the printing roller and a pressure roller.

Since both the pattern roller and the printing roller are continuously rotated, the pigment not imprinted upon the material is carried around by the rotation of the printing roller and forms a secondary pattern out of context with the freshly imposed pattern of the pattern roller. This problem has always existed to a degree, but is now enlarged by use of some of the new pigments and at the same time has become more objectionable by reason of the increased desire to achieve maximum design definition. Additional problems of unwanted carryover develop from increased use, in the wallpapering industry for example, of coated base papers. One such coating is of metallic or mica flakes. Bits of metal or mica tend to ride over after the printing roller contacts the paper being printed, adding to the indefiniteness of the successive printings of the roller. Also the buildup of these flakes results in lack of pigment adhesion to the gelatin roller.

The invention provides means for obviating such difficulties. The apparatus of the invention which may be embodied in a device for transferring a continuous pigmented design from a pattern roller to a material by means of an intermediate gelatinous printing roller impressing against the surface of the material comprises means for continuously pigmenting the pattern roller and solvent containing means mounted against the printing roller surface. The printing roller transfers its imposed pattern upon the surface of the material as the material passes between the printing and pressure rollers. The solvent containing means are mounted in that region of the printing roller surface travelling from the region of printing contact with the material toward patterning contact with the pattern roller. The solvent containing means is adapted for maintaining a pigment solvent in contact with the printing roller surface.

The solvent containing means may be a solvent well co-extensive with the effective length of the printing roller and maintaining a pigment solvent in contact with the surface of the printing roller. The solvent thoroughly cleanses the surface of the roller so that a pristine area is presented for receiving the pattern from the pattern roller. The solvent circulates constantly so that the dis-

2

solving action does not deteriorate during any period of operation.

The area of the roller which the solvent contacts must be limited. Carryover of solvent would adversely affect the pigment pattern renewed on the printing roller with each revolution. Therefore, in the preferable embodiment of the invention a first and a second solvent barrier are provided. Preferably, the first solvent barrier forms a part of the wall of the solvent well adjacent the printing roller surface. The first solvent barrier may take the form of a flexible blade held in contact with the printing surface and preventing the passage of solvent along the printing roller in the direction of its contact with the material to be printed. The second solvent barrier may be a second flexible blade contacting the surface of the printing roller between the solvent well and the region of pattern transfer to the printing roller.

Preferably, means are provided for adjusting the contact pressure between the solvent barriers and the printing roller and for removing the solvent barriers and the solvent well from proximity with the printing roller.

The end walls of the solvent well may be provided with seals to prevent passage of solvent from the well past the ends of the roller.

Further advantages of the invention are apparent in the following detailed description and drawing in which the drawing represents in schematic sectional elevation a rotogravure printer embodying the invention.

In the figure a press framework 10 having end pieces 30 such as end piece 12 supports a pattern roller 14, a printing roller 16 and a pressure roller 18. The pattern roller and the pressure roller are each in contact with the printing roller. The end frames support conventional journaling and power transmitting means (not shown) for the rollers. A strip of material such as wall paper 20 passes between the pressure roller and the printing roller. It may have a source such as a drum roll (not shown). An end 21 of the paper may be conveyed to further processing such as drying or overprinting. A flat bed 23 supports the paper as it emerges from between the pressure and printing rollers.

A pigment well 25 mounted adjacent pattern roller 14 supplies pigment continuously to the pattern roller. The well extends from end to end of the pattern roller and has an applicator brush 27 of metallic ribbon for distributing the pigment on the pattern roller. A crank and screw 29 bear against a protruding flange 31 of the well and apply a loading pressure against the pattern roller.

The pigment well may contain any of the conventional printing pigments dissolved in various solvents such as varnish, oils, etc. The pigment may contain finely divided metallic particles to impart a lustrous background to the material to be printed.

Printing roller 16 has an outer surface 32 of a gelatinous character. The gelatin may be the conventional coating used for many years for rotogravure printing or a newer gelatin such as those based on styrene plastic. Either of the surfaces mentioned receives an embossed pattern readily.

A solvent containing means such as solvent well 35 is supported upon a pair of rails such as rail 37 slideable horizontally in a way 39 fixed to end 12 of the printing frame. The solvent well comprises a horizontal bottom 41 extending from rail to rail between the ends 12. The bottom supports a back wall 43 and a front wall 45 adjacent the printing roller. Each of these walls is co-extensive with the bottom of the solvent well. The well has a pair of sides such as side 47 adjacent an end of the pressure roller. Each side slopes upwardly from the back wall toward the printing roller. The edge of the side adjacent the printing roller has an arcuate shape concentric with the periphery of the roller. A seal such

as end seal 49 makes sliding contact with the printing roller surface and prevents passage of the solvent contained in the well between the side of the well and the roller.

The front wall of the solvent well is considerably lower than back wall 43. Attached to the inner surface of the front wall is a first solvent barrier 51 shown in substantially tangential contact with the surface of the printing roller. The first barrier extends parallel to the axis of the printing roller from end seal to end seal of the solvent well. The first solvent barrier may be a strip of thin flexible material and not only serves as a partial front wall of the solvent well, but when in proper contact with the printing roller, prevents the pigment solvent in the well from coursing downwardly along the surface of the printing roller to the region of printing contact of the roller with the material.

A second solvent barrier 55 is held in substantially tangential contact with the surface of the printing roller between the solvent well and the region of contact between the printing roller and the pattern roller. The second solvent barrier may be a thin flexible metallic strip extending parallel to the axis of the printing roller from end seal to end seal.

The second solvent barrier is held in movable contact with the printing roller by a pair of L-shaped brackets such as bracket 57 pivoting about a rod 58 extending between printing frame ends 12. A screw and crank 59 are connected to bracket 57. Rotation of the crank changes the position of the second barrier.

It is preferable that the solvent be circulated in the well so that fresh solvent is maintained against the surface of the printing roller. Therefore, a pump 61 adapted to move solvent from a reservoir 63 to a bottom inlet 65 of the solvent well is regulated by conventional means to provide a measured flow of solvent into the well. An upper overflow 67 returns the same measure of solvent to the reservoir. Various reclamation means such as filters may be used to insure a supply of effective solvent from the reservoir to the well.

The rails 37 sliding in ways 39 are preferable to adjust the position of first solvent barrier 51 and the solvent well with respect to the surface of printing roller 16. The left hand end of each rail, as viewed in the figure, has a rack portion 71 meshed with a spur gear 73 turnable by means not shown. Rotation of spur gear 73 moves rail 37 within the way and changes the contact of first solvent barrier 51 with the printing roller. A shaft 74 connects spur gear 73 to a like gear meshed with like components on the opposite side of the frame (not shown) so that the well moves smoothly. Rotation in counter-clockwise direction removes the solvent well and the first barrier from proximity with the printing roller. The positions of the second solvent barrier and the pigment well with respect to the printing roller and the pattern roller are changeable. Each may be moved so that the contact pressure against the instant roller is increased. Conversely, each may be moved from contact with the roller. The provisions for adjustment of the solvent well, the solvent barriers and the pigment well make possible convenient substitution of different rollers in the printing frame.

In operation the rotogravure pattern roller is pigmented by the pigment well and rotates into contact with the printing roller. The printing roller receives the pattern impression and pigment from the pattern roller and rotates into contact with the material to be printed. The pressure roller insures contact of the material with the printing roller and transfer of the pattern is effected as the material passes between the printing and pressure rollers. The surface of the printing roller with whatever residual pigment remains on the surface, then revolves into the region of contact with the solvent in solvent well 35. The front wall of the solvent well differs sufficiently from the back wall in height so that a substantial area

of solvent is in contact with the printing roller surface. The solvent dissolves the residual pigment and a clean printing roller results. The first solvent barrier precludes leakage of solvent downwardly toward the material and the second solvent barrier contacts the printing roller surface so that no solvent is carried by the printing roller into the region of patterning contact.

Therefore, the printing surface roller presented to patterning contact with the pattern roller is free of any residual material, and a perfect pigment and pattern imprint may be transferred to the surface of the printing roller. No design fuzziness is present when the cleansed pattern portion of the roller imprints upon the material. The ability of the printing roller to transfer a finely detailed pattern is increased because the continuously cleansed roller surface takes and imparts a more exact pattern.

I claim:

1. In an apparatus for transferring a continuous pigmented design to a material, a pattern roller, a pressure roller, a gelatinous printing roller vertically disposed above the pressure roller, said printing roller impressing the surface of the material as the material passes between the printing roller and the pressure roller, means for continuously pigmenting the pattern roller, a pigment solvent well coextensive with the effective length of the printing roller, a first solvent barrier co-extensive with the effective length of the printing roller and supported by the pigment solvent well, a second solvent barrier co-extensive with the effective length of the printing roller, and seals adjacent each end of the printing roller precluding passage of pigment solvent from the solvent well at the ends of the printing roller, the solvent well being positioned with respect to the printing roller so that a peripheral segment of the printing roller surface travelling from the region of contact with the material toward patterning contact with the pattern roller is directly contacted by a pigment solvent contained in the solvent well to wash from the printing roller pigment carried over from the printing contact with the material.

2. In an apparatus for transferring a continuous pigmented design to a material, a pattern roller, a pressure roller, a gelatinous printing roller vertically disposed above the pressure roller, said printing roller impressing the surface of the material as the material passes between the printing roller and the pressure roller, means for continuously pigmenting the pattern roller, a pigment solvent well co-extensive with the effective length of the printing roller, the solvent well being positioned with respect to the printing roller so that a peripheral segment of the printing roller surface travelling from the region of contact with the material toward patterning contact with the pattern roller is directly contacted by a pigment solvent contained in the solvent well, a first solvent barrier co-extensive with the effective length of the printing roller and supported by the pigment solvent well, a second solvent barrier co-extensive with the effective length of the printing roller, seals adjacent each end of the printing roller precluding passage of pigment solvent from the solvent well at the ends of the printing roller, means for adjustably positioning the first solvent barrier relative to the surface of the printing roller and means for adjustably positioning the second solvent barrier relative to the surface of the printing roller.
